UNITED STATES PATENT OFFICE

2,613,108

FLUID DISPENSER

George F. Kraus, Camden, N. J.

Application April 1, 1949, Serial No. 85,007

6 Claims. (Cl. 299—25)

1

This invention relates to improvements in means for the periodic and automatic dispensing of fluids.

The primary object of this invention is the provision of a relatively simple and compact mechanism for the automatic and periodic dispensing of fluids such as deodorants, air purifying agents, germicides, antiseptics, insecticides, etc.

A further object of this invention is the provision of improved means for the automatic dispensing of fluids which are normally maintained under superatmospheric pressure.

A further object of this invention is the provision of improved means, adapted for use in laboratories, store rooms, theaters, auditoriums, restaurants, hospitals, transportation vehicles, hotels, etc., for the periodic dispensing of deodorants and air purifying and cleansing agents from automatic pressure type dispensers wherein the active fluid is maintained under superatmospheric pressure by means of a liquefied gas.

Other objects and advantages of the invention will be apparent from the following detailed description.

In the accompanying drawings, forming a part of this specification, and wherein similar reference characters designate corresponding parts throughout the several views—

Figure 1 is a front elevation of the improved device.

Figure 2 is a rear view of the device with the rear cover removed.

Figure 3 is a vertical cross sectional view taken substantially on the line 3—3 of Figure 1.

Figure 4 is an enlarged fragmentary view showing the gear train of a speed reduction mechanism associated with the improved device.

Figure 5 is a fragmentary cross sectional view taken substantially on the line 5—5 of Figure 1.

Figure 6 is a cross sectional view taken substantially on the line 6—6 of Figure 3 showing the actuating mechanism.

Figure 7 is a fragmentary vertical cross sectional view taken thru the speed reduction and other clockwork operated mechanism of the device.

Figure 8 is a fragmentary view showing a modified form of operating mechanism.

Figure 9 is a fragmentary cross sectional view showing the means for actuating the valve mechanism of a fluid pressure dispenser of the operating mechanism of Fig. 8.

In the drawings, wherein for the purpose of illustration are shown preferred and modified forms of the invention, the letter A may generally

2

designate the improved device. It consists of a framework or casing structure B, adapted to support a pressure type fluid dispenser C. The framework or casing structure B also supports a clockwork mechanism D having means E associated therewith for operating the valve mechanism of the pressure dispenser C.

Referring to the dispensing receptacle C, the same includes a container body 20 of cylindrical form having a bottom wall 21 and a preferably reduced neck 22 which supports a valve mechanism (not shown) ordinarily operated by means of a laterally movable stem 23. One such type of receptacle is shown in U. S. Patent No. 1,892,750.

The receptacle is adapted to contain some solution of material to be atomized. It is hermetically sealed and the solution is maintained under superatmospheric pressure by means of a liquefied gas under pressure not less than the liquefaction pressure of the gas used. Upon tilting of the stem 23 the nozzle and valve mechanism (not shown) are actuated to release pressure so that the solution of material, which may be a deodorant, air purifying agent, germicide, antiseptic, etc. is dispensed in an atomized condition.

The frame or casing structure B is provided with top and bottom walls 24 and 25, and side walls 26. The front wall 27 has an opening 28 cut to the contour or outline of the container C, just sufficient to permit a segment of the container to rest therein with its bottom wall 21 upon the resting surface of the opening 28 and the reduced neck 22 seated at 29 in said opening. Thus the major portion of the dispensing receptacle and particularly the valve are in the clear so that the atomized fluid may be dispensed externally of the casing. The container C is supported in this position by means of a flexible band or loop 31, shown best in Figure 5; the same being secured at 32 at one end and adapted to loop about the neck 22 of the container C; the free end thereof being provided with an opening 33 adapted to receive a threaded shank 34 upon which a detachable nut 35 operates. Turning the nut 35 will permit the container to be clamped in position by the band 31 or released, as is quite obvious.

The clockwork mechanism D preferably comprises a frame structure consisting of front, intermediate and rear plates or discs 40, 41 and 42, of circular form, detachably connected in relatively spaced relation by bolt and nut means 42a. This framework is detachably connected by nuts

44 to a supporting plate or disc 45 which is detachably screwed or connected at 47 within the compartment of the casing B, so that the entire clockwork mechanism D may be disposed in said compartment, as shown in Figure 3. A detachable rear closure 50 is provided for closing the compartment.

The clockwork mechanism D furthermore includes an electric motor 55 detachably mounted upon the rear surface of the rear plate 42, as shown in Figure 7 of the drawings, and elsewhere. The motor 55 is provided with a shaft 56 having a pinion 57 keyed thereon lying between the frame plates 41 and 42. This pinion meshes with a larger gear 58 which is keyed upon a shaft 59 bearing upon and between the plates 41 and 42. To the shaft 59 is keyed a pinion 60 which meshes with a larger gear 61 keyed upon a shaft 62 supported upon the plate 42, as shown in Figure 9. The shaft 62 has a pinion 64 keyed therewith which meshes with a larger gear 65 keyed upon a shaft 67 which bears at one end upon the plate 42 and at its opposite end has a step bearing in a rotatable shaft 68 to be subsequently described; the latter bearing in the frame plates or discs 40 and 41, as shown in Figure 7. Further gear reduction for the clockwork mechanism comprises a pinion 70 keyed upon the shaft 67 in mesh with a larger gear 71 keyed upon a shaft 72 which bears upon and between the plates 41 and 42. The shaft 72 also has a pinion 74 keyed therewith which meshes with a larger speed reducing gear 75 keyed upon that portion of the shaft 68 which lies between the plates 41 and 42.

Referring at this time to the mechanism E for actuating the valve stem 23 of the dispensing receptacle, the same comprises a shaft 80 rotatably bearing upon the frame structure B, preferably in the front wall 27 thereof, as shown in Figure 3. This shaft 80 is horizontally positioned and may also bear in the rear closure 50, as shown. It projects forwardly from the wall 27 and is provided with a crank arm 82 adapted to engage and tilt the valve stem 23, for the purpose of actuating the valve of the dispensing container for atomizing release of the fluid to be dispensed. Within the compartment of the casing B there is provided a depending arm 85 keyed upon the shaft 80 which is adapted to be engaged by the trip lever 90 of the clockwork mechanism. The trip lever 90, as is shown in various views of the drawings, is pivoted at 91 (Fig. 6) upon a shaft which is supported by the plates 40 and 41 of the clockwork frame.

The clockwork shaft 68 which is driven at a very slow rate of speed thru the gear reduction mechanism above described has a hub 100 keyed therewith to which the inner end of a spiral spring 101 is keyed or welded at 102. The spiral spring 101 at its opposite end is keyed or welded at 103 to a trip lever actuating arm or lug 105 which is fixedly connected upon a disc 106 forming part of a nut 107 threaded upon the threaded portion 108 of shaft 68.

The trip lever actuating lug or arm 105 is normally urged by the leaf spring 101 in a direction to actuate the trip lever 90, so the latter will move against the shaft operating arm 85 and throw the crank 82 into operation for tripping the stem 23 and actuating the valve mechanism of the atomizing container.

The normal action of the spring 101 is restrained by a detent spring arm 110 which is fixedly secured at 111 upon the frame disc 41. A timing adjustment screw 112 may be provided,

in threaded relation upon the disc 41 for moving the inner end of the detent 110 along the trip lever actuating lug 105, so the latter may be controlled as to its releasing action according to the periodicity with which it is desired to release the fluid from the pressure container.

The sequence of operation is as follows:

Thru the gearing and shafting above described the shaft 68 is rotated in the direction indicated by the arrow in Figure 7. The turning of the shaft is very slow and as it rotates it winds up the leaf spring 101 for storing up power therein. Of course the outer end of the spring is restrained from moving by engagement of the trip lever 15 actuating lever arm 105 against the detent 110. As the shaft 68 slowly rotates the nut 107 will be fed along the shaft in the direction of the frame plate 40 and this moves the trip lever actuating arm 105 in a direction away from the detent 110. When the tip end of the lug 105 has cleared the detent 110 the spring 101, which is secured to the lug 105, will throw the latter in the direction of the trip lever 90 and engaging the trip lever will throw the latter against the arm 85. 20 The shaft 80 is turned, and the crank 82 thrown against the stem 23 for releasing the valve and dispensing the pressure fluid from the container. The nut 107 rotates upon the threaded portion 25 of the shaft 68 incident to action of the spring 101 and will move along the threaded portion 108 in the direction of the spring 101. This will bring the lug 105 again into position for engaging the detent 110. The cycle, of course, is repeated 30 according to the gearing setup. The timing may be varied thru the adjustment screw 112 since the spring end of the detent arm 110 may be moved along the lug or arm 105 to vary the dispensing period.

In Figures 8 and 9 is shown another form of 40 invention. In this form of invention the dispensing container C' is provided with a depressible ball 23^a which causes the fluid to be dispensed from the pressure container. To that end the shaft 80^a is provided with a crank 82^a 45 having a roller 82^b on the end thereof normally urged against and in the direction of the ball 23 by means of a spring 82^a which is attached to the shaft arm 85^a, as shown in Figure 8. The trip lever and operating mechanism are the same 50 as above described. When the trip lever 90^a moves to throw over the arm 85^a against the tension of the spring 82^a, the shaft 80^a will be rotated to throw the roller 82^b across the ball 23^a and depress the same to cause the pressure fluid 55 to be dispensed from the container C'. Of course the spring 82^a returns the roller 82^b to a reset position.

Various changes in the shape, size and arrangement of parts may be made to the form of the 60 invention herein shown and described without departing from the spirit of the invention or the scope of the following claims.

I claim:

1. In an automatic dispensing device the combination of a supporting frame, clockwork mechanism supported by said frame including gear reduction mechanism and a shaft slowly driven thereby, said shaft having a screw threaded portion, a nut threaded upon said shaft for movement therewith as the shaft rotates, a spring normally rotatably urging said nut to rotate in one direction upon said shaft, a fluid dispenser carried by said frame having a fluid releasing member, movable means carried by the frame to operate said member, said nut having means as-

sociated therewith to engage and operate the movable means upon rotation of the nut by said spring, and detent means to restrain rotation of the nut until said shaft has been turned to a predetermined extent sufficient to feed the nut along the screw threaded portion of the shaft out of the path of said detent means.

2. In a device for dispensing fluids under pressure the combination of a supporting casing, a dispensing container carried by the casing having a fluid therein under superatmospheric pressure and valve means including an actuating member movably supported by the container, means to detachably support said container upon said casing, means mounted upon the container for actuating said valve actuating member, and clockwork actuated means mounted upon the casing for actuating the last mentioned means periodically.

3. In a dispenser for period release of fluids, the combination of a supporting frame, a trip lever movably mounted upon said frame, clockwork mechanism carried by the frame, a shaft, gear reduction mechanism actuated by the clockwork mechanism to rotate the shaft at a slow rate of speed, said shaft having a screw threaded portion thereon, a nut threaded upon the threaded portion of the shaft for movement therealong, a spiral spring keyed at one end to the shaft, means keying the other end of the spring with the nut so that as the shaft rotates the spring will be wound for the purpose of storing power therein, detent means carried by the frame, and means carried by the nut associated with the detent means to restrain said rotation of the nut under influence of the spring until the nut has moved a predetermined distance along the threaded shaft as an incident of rotation of the shaft, said nut having means thereon to actuate said trip lever when the last mentioned means as an incident of movement of the nut along the shaft has moved out of the path of the detent means, and means mounted upon the frame having a fluid under pressure therein including a valve in position to be periodically operated by said trip lever to release said fluid.

4. In a dispenser for period release of fluids, the combination of a supporting frame, a trip lever movably mounted upon said frame, clockwork mechanism carried by the frame, a shaft, gear reduction mechanism actuated by the clockwork mechanism to rotate the shaft at a slow rate of speed, said shaft having a screw threaded portion thereon, a nut threaded upon the threaded portion of the shaft for movement therealong, a spiral spring keyed at one end to the shaft, means keying the other end of the

spring with the nut so that as the shaft rotates the spring will be wound for the purpose of storing power therein, detent means carried by the frame, and means carried by the nut associated with the detent means to restrain said rotation of the nut under influence of the spring until the nut has moved a predetermined distance along the threaded shaft as an incident of rotation of the shaft, said nut having means thereon to actuate said trip lever when the last mentioned means as an incident of movement of the nut along the shaft has moved out of the path of the detent means, the spring actuating to rotate the nut upon the shaft and return the nut to a reset position of the means carried by the nut with respect to the detent means, and means mounted upon the frame having a fluid under pressure therein including a valve in position to be periodically operated by said trip lever to release said fluid.

5. In a dispensing device the combination of a supporting frame, a container having a sanitizing fluid hermetically sealed therein in association with a liquefied gas under pressure sufficient to maintain the gas liquefied until released from the container, valve means upon the container, means for supporting the container upon the supporting frame, and clockwork means carried by the frame to periodically actuate said valve for pressure release of said sanitizing fluid as gaseous vapor from the container.

6. In a dispensing device the combination of a supporting frame, a container having a sanitizing fluid hermetically sealed therein in association with a liquefied gas under pressure sufficient to maintain the gas liquefied until released from the container, valve means upon the container, means for supporting the container upon the supporting frame, clockwork means carried by the frame to periodically actuate said valve for pressure release of said sanitizing fluid as gaseous vapor from the container, and means for varying the period during which the clockwork mechanism actuates said valve.
